CLAIM

The ornamental design for a machine for vending nutritional information, as shown and described.

DESCRIPTION

FIG. 1 is a perspective view of a machine for vending nutritional information, showing my new design.

FIG. 2 is a front elevational view thereof.

FIG. 3 is a side elevational view thereof, the opposite side being the mirror image.

FIG. 4 is a top plan view thereof.

The bottom and rear are substantially plain and unornamented.

FIG. 1

FIG. 2

FIG. 3

FIG. 4
